Primary Examiner — Kevin Rudzinski

(57) **CLAIM**

The ornamental design for a computing device display screen with computer-generated application launch interface, as shown and described.

DESCRIPTION

The single FIGURE is a front elevation view of a computing device display screen with computer-generated application launch interface showing our new design.

The broken lines shown in the drawings are for the purpose of illustrating a display screen of a computing device, text, and other images, and form no part of the claimed design.
